UNITED STATES PATENT OFFICE.

HOWARD B. PERRY, OF WAKEFIELD, RHODE ISLAND.

DESIGN FOR AN EASEL.

SPECIFICATION forming part of Design No. 33,047, dated August 7, 1900.

Application filed June 11, 1900. Serial No. 19,969. Term of patent 14 years.

To all whom it may concern:

Be it known that I, HOWARD B. PERRY, a citizen of the United States, residing at Wakefield, in the county of Washington and State 5 of Rhode Island, have invented and produced a new and original Design for an Easel; and I do declare the following to be a full, clear, and exact description of the invention, such as will enable others skilled in the art to which o it appertains to make and use the same, reference being had to the accompanying drawing, and to the letters of reference marked thereon, which form a part of this specification.

5 My invention relates to a design for an easel usually placed upon show-cases and for holding photographs; and it consists in the shape and configuration, which will be more fully described hereinafter, whereby a very o light, substantial, and ornamental holder is produced.

The accompanying drawing represents an easel which embodies my invention in perspective.

5 A represents a triangular-shaped frame, of wire, which is curved so as to form the rings or circles B at its lower corners and which

has the cross-piece C, inclined upwardly from each side to a point D at its center. The rings B are inclined slightly forward and 30 away from the frame, leaving a space between them. At the top of the frame the wire is coiled together at F, and then it is curved downwardly and backwardly at an angle in double strands E, and the wire is again twisted together at G. Below this twisted portion G the ends H of the wire are inclined outwardly and downwardly and terminate in the loops I, which form supporting-feet.

It will be seen that the triangular-shaped 40 frame and the supporting portions E G H are placed at an angle to each other and that the frame has four supporting points or feet.

Having thus described my invention, I 45 claim—

The design for an easel substantially as shown and described.

In testimony whereof I affix my signature in presence of two witnesses.

HOWARD B. PERRY.
